AUTOMATIC SPRAYING MACHINE

Svend Bramsen, Eric Gustafsson, and Fred W. Wahlin, Chicago, Ill., assignors to Binks Manufacturing Company, Chicago, Ill., a corporation of Delaware

Application November 8, 1937, Serial No. 173,366

9 Claims. (Cl. 91—45)

The present invention relates to spraying devices and more particularly to machines for automatically spraying such articles as have flat or substantially flat surfaces so as to coat the same with sprayed material, such as vitreous enamel, ceramic material, synthetic enamel, lacquer, paint, asphaltic compounds for sound deadening, etc.

Among the objects of the invention is to provide a novel spraying device for automatically 10 coating the surface of an article being moved in a given path, as on a travelling conveyor, by giving the spraying means movements across the line of travel of the article in given time relation thereto so that the coating will be uniform over the whole extent of the sprayed surface, and automatically controlling the time of spraying in accordance with the width of the surface being sprayed, as well as discontinuing the spraying, when the movement of the article 20 ceases, to prevent spoiling the coating.

More specifically, the invention comprehends a reciprocating carriage so mounted as to be reciprocated straight across or more or less diagonally across the path of movement of the article 25 at given speed, the carriage carrying one or more spray guns, preferably of the type which produces flat sprays, and means for regulating the duration of the spraying during the reciprocation of the carriage in accordance with the width of the surface of the article being coated. Such means is preferably of the adjustable type and is so located that as the spraying gun or guns pass from over the surface being sprayed the spraying 30 action will stop regardless of the length of the stroke of the carriage, or in other words, the spraying is effective only during the time the gun or guns are over the surface of the article being coated. One of the advantages in this is a great economy in the spraying material used, which is highly important in the case of using 35 expensive material, besides preventing a scattering of wasted material in and about the device where it would clutter the mechanism, reduce its efficient operation, increase its wear and 40 decrease its life, require frequent cleaning and increased labor and maintenance costs, etc.

The governing or control means for the duration of the spray, in the illustrative embodiment, comprises a pair of cams which are adjustable 50 to and from each other depending upon the length of spray stroke desired and are so located as to be in the path of reciprocation of a means for controlling, that is, for starting and stopping, the operation of the triggers of the spray guns. 55

This spray operation controlling means is carried by the reciprocating carriage, and although it has the same fixed stroke of the carriage, it so operates the spraying means that the duration of the spraying will be for a portion of that stroke of the carriage and the parts carried by the carriage. The part of the stroke during which spraying occurs may be termed the spraying stroke.

The spray operation controlling means is in the nature of a rocker arm or lever, pivotally mounted on the carriage with an end thereof so disposed as to have a path of movement in the space between the cams so that as such end of the lever moves toward either cam, it will engage the one or the other of the cams whereby the lever will be rocked to shut off the spray guns. The other end of the lever is connected to means for operating the spray gun triggers, so that as the lever is rocked, as by a spring, to one position, that is, to the position in which it travels freely between the cams, it operates the triggers to open the spray guns whereby a spray is effected during the time and for the distance the rocker arm is travelling between the cams, which is for a part of the stroke of the carriage, and as the lever is rocked to another position, that is, when it engages a cam so as to be rocked thereby, it so operates the triggers as to shut off the guns and stop the spraying.

The invention comprehends a novel means for operating the guns, such means comprising a trigger lifter so disposed as to raise or swing the triggers of the guns, in unison when there are more than one gun in use, to cause the guns to spray, and to effect a lowering of the triggers, also in unison when more than one gun is used, to shut off the guns and stop the spraying. This lifter is connected to the rocker arm and is operated in one direction, lifting direction, by a spring, and in the other direction, lowering direction, to cause shutting off of the guns, by the cams as the rocker arm engages them when moving in a direction toward the ends of the strokes of the carriage.

As another feature of the invention, the latter comprehends a novel carriage having means for reciprocatingly moving along a track or tracks disposed transversely of the travel of the article being sprayed, and having a frame carrying a vertical track or tracks along which vertically reciprocates a slide body, such as a block, with rollers rolling along such vertical track or tracks, the block having a connection, such as a pin, with an endless chain operating over sprocket

wheels which are so disposed that the laps of the chain between them travel horizontally and transversely of the path of travel of the article being sprayed, and the chain portions passing around the sprocket wheels will give the pin and the connected vertically movable slide body a vertical component movement at the ends of the strokes of the carriage. The horizontal laps of the chain between the points of contact between such laps and the sprocket wheels travel at constant speed so that the carriage has a constant speed of reciprocating movement throughout the effective length of its strokes, the effective length of the stroke being taken as that length of the horizontal laps of the chain between their tangential points of contact with the sprocket wheels, the remaining component horizontal movements beyond such effective stroke lengths, arising by reason of the chain link carrying the pin around half of each sprocket wheel, not being regarded as part of the effect length of the strokes.

The invention also comprehends as a feature thereof, the provision of a novel support for the spraying means, the means for operating the spraying means, and the means for supplying the material and spray producing fluid to the spraying means. In the illustrative embodiment this feature comprises a vertically disposed frame structure carried by the carriage and having laterally extending and vertically spaced brackets to which are adjustably clamped vertical tubes in which the ducts or pipes to the guns for conveying material to be sprayed and compressed air are located, and to the lower of which brackets are connected material and air manifolds and the guns themselves, the brackets also having suitable apertures for the passage of a vertical rod connected to a trigger lifter and to the rocker arm, the rocker arm being pivotally mounted on the upper of such brackets.

Another object of the invention is the provision of means for stopping the spraying when the travel of the article being sprayed stops traveling. In the embodiment chosen to illustrate the invention, such a means comprises a pneumatically operated piston and piston rod which coacts with the previously mentioned spray controlling rocker arm or lever to so move it as to shut off the spray guns when the circuit to the conveyor motor is opened. While the switch in this circuit is conventionally shown it is to be understood it may have an overload circuit breaker adapted to open the circuit should the conveyor become stuck or an overload be so imposed on it as to slow up its travel or to stop it entirely. The piston and its rod, normally held in inactive position by a spring, are operated pneumatically, that is, by compressed air as may be admitted by a valve connected to an electro-magnet in a circuit in shunt with the circuit to the conveyor motor, whereby as the circuits are opened the solenoid of the electro-magnet is deenergized and the air valve is so operated as to admit compressed air to the piston device and thus operate the rocker arm or lever to shut off the spray guns. Accordingly, the spraying may stop at substantially the same instant as when the conveyor stops travelling, and then remain in that condition regardless of any continued reciprocation of the carriage. So soon as the conveyor motor circuit is closed or re-established, the solenoid is energized so as to shift the air valve and to exhaust the compressed air from the piston device, the rocker arm being

5 returned to its inactive position by the spring when the cam engaging end of the rocker arm is in its path of travel between the cams, at which time the spraying action is started.

10 The invention preferably also comprehends the provision of means for shutting off the spraying only at an end of the spraying stroke when the circuit to the conveyor motor is opened, the movement of the conveyor and of the carriage continuing after the conveyor motor circuit is opened to the point where the reciprocating carriage has reached the end of the spraying stroke, that is, both the conveyor and the reciprocating carriage come to a stop after the spraying across 15 the surface of the article has been completed, thus avoiding the stopping of the spraying at some intermediate point of the spraying stroke. This is effected by providing a shunt circuit connected to the carriage reciprocating motor and to the conveyor motor circuits with means connected to and actuated by the rocker arm for opening such shunt circuit at the time when the control cam, with which the rocker arm engages, rocks the rocker arm. The motor circuits have 20 relay controlled circuit breakers for opening the circuits when the relay means is deenergized or partly deenergized by the opening of the shunt circuit by the rocker arm.

25 The invention may also comprehend novel means for so disposing the device as to reciprocate the carriage not only straight across the path of travel of the article being sprayed but also transversely at any desired or given angle to such path. In such case the device may be mounted as to turn about an axis perpendicular to the plane of the conveyor, as on a turntable which may be angularly adjusted to the desired angle between the line of reciprocation of the carriage and the line of movement of the article.

30 Other objects, capabilities, advantages, features and the like are comprehended by the invention as will later appear and as are inherently possessed by the invention.

Fig. 15 is a top plan view showing the difference of spraying straight across and diagonally or angularly across a narrow object.

Referring more in detail to the drawings, the embodiments selected to illustrate the invention are shown as comprising an endless rope conveyor 1 passing over pulleys 2 and 3 (Figs. 1 and 2) suitably rotatably supported in stands 4 and 5, and driven by a motor 6 operating through a reducing drive 7 and pulley 8.

The conveyor passes through chambers 9, 10 and 11 in which spraying of conveyed articles 12 may occur, the spray device 13, shown in general in Figs. 1, 2 and 3, operating in chamber 11 for automatically spraying the top flat or substantially flat surface of the article 12 as it is conveyed through the chamber 11.

When spraying flat articles without side walls, the spraying is effected in the chamber 11 only. When articles to be sprayed have also side walls, such as flanges 14, these flanges are sprayed by workmen stationed at the chambers 9 and 10 by spraying through the windows 15 and 16, as the article passes through the chambers 9 and 10, and the top surface of the article is automatically sprayed in the chamber 11 as the article passes therethrough, the workmen standing at opposite sides of the machine at locations or loci 17 and 18 at the sides of chambers 9 and 10 respectively.

The conveyor may, if desired or found necessary, have upwardly extending pins 19 for supporting the article out of contact with the conveyor. When using a rope type of conveyor, the use of pins may be inconvenient and in that case the article will be supported directly upon the ropes. The tautness of the conveyor may be adjusted by suitable adjusting screws 20 on the stand 4 (Figs. 1 and 2).

The automatic spraying device in the chamber 11 is shown more in detail in Figs. 4, 5, 6, 7, 8, 9 and 10, and comprises spaced supporting standards or posts 21 and 22 of tubular or hollow cylindrical form and fixed at their lower ends to pedestals 23 and 24 seating on and/or fastened to the floor of the chamber 11 at the sides thereof.

Secured to these posts is a channel iron cross beam 25 which extends transversely of the chamber 11 and at an adjustable elevation. The web part 25a of the beam 25 is clamped or bolted to box-like brackets 26 and 27 which have curved recesses for receiving side portions of the posts 21 and 22 (see Fig. 2) and which are held clamped to the posts by U-bolts 28 and 29, these bolts passing around the posts and through the brackets 26 and 27 and the web 25a of the beam 25 where their ends are threaded to receive clamping nuts.

Beneath the brackets 26 and 27 are adjusting brackets 30 and 31 which are clamped to the posts 21 and 22 by U-bolts 32 and 33 passing around the posts 21 and 22 and through the adjusting brackets 30 and 31 to suitable clamping nuts. These brackets 30 and 31 carry adjusting screws 34 and 35 the upper ends of which contact the lower sides of the brackets 26 and 27.

For adjusting, the U-bolts 28 and 29, as also 75

U-bolts 32 and 33, are loosened and the beam 25, together with the parts carried thereby, is moved vertically approximately to the desired point, and the adjusting brackets 30 and 31 are also likewise moved. Then the U-bolts 32 and 33 are tightened and the adjusting screws 34 and 35 are rotated to effect a fine adjustment of the beam 25 and the parts carried thereby to exactly the desired position. Then the U-bolts 28 and 29 are tightened.

Along the flanges of the beam 25 are located tracks 36 and 37 suitably secured to the flanges, as by screws or bolts. These tracks are octagonal in cross-section and upon the inclined faces thereof reciprocatingly roll rollers 38 and 39 carried by roller supports 40 and 41 each in the form of an elongated bar (see Fig. 5). These bars 40 and 41 are bolted to upper and lower cross heads 42 and 43 of a vertically disposed elongated rectangular carriage frame 44. Suitable adjusting screws 45 and 46 are carried by the cross heads 42 and 43 and coast with the roller carriers 40 and 41 for adjusting the rollers 38 and 39 to the tracks 36 and 37 for smooth reciprocation of the carriage along the tracks.

Integral or rigid with the cross heads 42 and 43 are laterally extending brackets 47 and 48 to which are clamped vertical tubes 49 and 50 by clamping cleats 51 and 52 secured by suitable clamping bolts. To the tubes 49 and 50 are secured, as by suitable bolts or screws, guide heads 53 and 54 which are suitably apertured for the vertical reciprocation therein of a vertical trigger operating rod 55, the upper end of the rod 55 being pivotally connected to a rocker arm 56 suitably secured to a shaft 57 having suitable bearings in a bracket 58 secured to the top of the upper crosshead bracket 47.

The upper end of the rod 55 carries a head 59 against which presses the upper end of a helical spring 60 which surrounds the rod 55, as shown in Figs. 4 and 6, the lower end of the spring pressing on a support 61 carried by the cross head 58. The brackets 47 and 48 have large openings 62 and 63 for the free passage of the rod 55 and spring 60. The lower end of the rod 55 is secured to a tube 64 which reciprocates in the crosshead 58 (see Fig. 6), and this tube is threaded to an upwardly extending arm 65 of a trigger lifter crosshead 66. This head carries fixed angle brackets 67 and 68 for lifting triggers 69 and 70 of the spray guns. In the device illustrated there are four guns (only three being shown) and the end guns have triggers 69 and the intermediate guns have triggers 70.

The bracket 58 carries an adjusting screw 71 to act as an abutment for the movement of the rocker arm 56. On the bracket 58 is also fixed a cylinder 72 in which a piston 73 is normally pressed upwardly by a spring 74, the piston carrying a piston rod 75 the lower end of which is opposite and normally spaced from a button 76 carried by the rocker arm 56. At the upper end the cylinder 72 has an air inlet-outlet 77 connected to a compressed air hose 78. When compressed air is admitted by way of the hose 78 into the cylinder 72, the piston 73 and the rod 75 are depressed and the rocker arm 56 so rocked as to move the trigger operating rod 55 downward and hence the trigger brackets 67 and 68 so that the triggers 69 and 70 swing downwardly and close off the guns.

At the other end of the rocker arm 56 is secured, as by a set screw, a bearing screw 79 for rotatably carrying a cam roller 80 which is adapt-

ed to ride up upon the cams 81. There are two of these cams, one at each end of the cross beam 25 so that as the reciprocating carriage arrives at the ends of its stroke the cams will be so located as to cam up the roller 80 and the rocker arm 56 so as to depress the trigger operating rod 55 and hence the lifter brackets 67 and 68 to permit the triggers 69 and 70 to shut off the guns and stop the spraying.

The cams 81 are adjustably supported and are fastened to cam bases 82 adapted to slide longitudinally on cam tracks 83 fixed to a base plate 34, by suitable screws (see Fig. 9), the screws serving to secure the assembly rigidly to the top of the cross beam 25. Each cam 81 is secured to its base 82 by suitable screws or the like, and has recesses for receiving upwardly extending lugs 85 and 86 of a nut 87 and a block 88 which are shaped to slide in the channel between the tracks 83 (see Figs. 8 and 9). The nut 87 is threaded to an adjusting screw 89 which has right and left hand threads at the end portions thereof for causing the nuts 87 and the cams 81 to mutually approach or separate when rotating the adjusting screw in one or another direction. The bore of the block 88 is unthreaded so that the block may slide without binding with the screw 89, the lug 86 serving to maintain the cam 81 aligned and to prevent its turning about the axis of the nut lug 85. The ends of the screw 89 are reduced in diameter to provide shoulders abutting end thrust blocks 90 which also serve as bearings for the ends of the adjusting screw 89. At one end the screw 89 has an extension to which is secured a hand wheel 91 (see Figs. 4 and 5) having a handle 92 by which the adjusting screw may be manually rotated and the cams adjusted to and from each other depending upon the direction of rotation of the screw 89.

The means for reciprocating the carriage is mounted on the cross beam 25. It comprises a motor 93 (see Figs. 4 and 5) suitably secured to the web plate 25a of the cross beam 25 and having a shaft 94 to which is secured a sprocket wheel 95 over which rides a driving chain 96 running over a sprocket wheel 97 fixed to a shaft 98 operatively connected to a speed reducing device 99 suitably fixed to the web wall 25a of the cross beam.

From the speed reducing device extends a shaft 100 (see Fig. 4) which passes through the web wall 25a and is rotatably supported in a bearing 101 fixed to the inside of the web wall 25a. To this shaft is secured a sprocket wheel 102 over which rides a chain 103 running to a sprocket wheel 104 fast to a shaft 105 rotatably supported in a bearing means 106 adjustably connected to the web wall 25a. (See Figs. 4 and 6.) To this bearing means is connected a chain tightener 107 secured to the web wall 25a and having an adjusting screw for adjusting the bearing means longitudinally of the cross beam 25 for tightening the chain when it becomes slack, a suitable slot being provided in the web wall 25a through which a part of the bearing means extends to the chain tightener 107.

The carriage frame 44 has spaced upright side posts 44a (see Figs. 6 and 7) to which are secured vertical channel tracks 108. In these tracks vertically reciprocates a slide body or block 109 having pivotally mounted rollers 110 at its corners and which travel vertically in the channels of the vertical tracks 108. See Figs. 4, 6 and 7. The center of the block carries a pin 111 one end of which is fast with a short

channel piece or clip 112 (Fig. 6) spanning and being fixed to a link of the chain 103. As the pin travels with the chain link the block 109 is caused to reciprocate vertically in the carriage frame tracks 44a while at the same time the carriage frame is given a horizontal reciprocation along the carriage tracks 36 and 37. The horizontal stroke of the carriage is equal to the distance between the axes of the sprocket wheels and the pitch diameter thereof. The vertical reciprocation of the block 109 is equal to the pitch circle diameter of either sprocket wheel 102 or 104, they being of the same size.

To prevent the block 102 from descending too low by reason of its weight and as may be permitted by reason of any slack in the lower lap of the chain 103, a lower limit stop 113 is fixed to the lower end of the carriage frame 44, as by a screw 114 (Fig. 6) and has a stop finger 115 so located that the lower end of the block 109 will abut it and be limited by it in the downward movement of the slide body or block.

The spray guns 120 and 121 are supported by way of air and material manifold mounting brackets. As shown in Fig. 4, a bracket 116 is secured to the cross head 54 and carries an air manifold 117 connected to a pipe 118 which is connected to the lower end of a hose 119 extending down in the tube 50, the upper end of the hose extending upwardly out of the upper end of the tube 50 to a compressed air source (not shown). The manifold 117 has connections 117a to the upper parts of the spray guns 120 and 121, there being in the illustrative embodiment four guns in a row at right angles to the line of reciprocation of the carriage, the end guns being designated 120 and the inner guns being designated 121.

From a suitable material source (not shown) runs a material duct or hose 122 which enters the upper end of the vertical tube 49 and extends downward for connection at its lower end to the upper end of a material pipe 123 leading to a manifold 124 having connections 125 to the lower portions of the guns (Fig. 6). The vertical tubes 49 and 50 together with the cross heads 53 and 54 and the other parts carried thereby and by the tubes 49 and 50 are vertically adjustable in the clamps 51 and 52. The spray guns used may be of the kind disclosed in the patent of Bramsen & Wahlin, No. 2,107,726, granted February 8, 1938.

In use the device is operated by motors 6 and 93, the motor 6 driving the conveyor and the motor 93 reciprocating the carriage. The spraying occurs during that part of the stroke of the carriage which corresponds to the length of the space between the cams 81 where the rocker arm roller 80 normally travels until it engages either cam to rock the rocker arm 56 and to depress the trigger lifter 66 and thus close off the spray guns.

Should the ware or article being coated by the spray be narrow the cam adjusting screw 89 is so manually operated as to move the cams 81 nearer to each other, as for example, as to the positions shown in dotted lines in Fig. 4, whereby the spray stroke will be shortened, that is, the spray guns will not spray for the remainder of the reciprocating strokes of the carriage beyond the sides or side edges of the ware or article the surface of which is being sprayed. In this way considerable saving of the material is effected, the spraying occurring only during

the passage of the guns over the width of the article being sprayed.

As shown in Fig. 11 the motors 6 and 93 are connected to circuits 126 and 127 having switches 128 and 129 and being connected to a main circuit line 130. In shunt with the conveyor motor circuit 126 is a solenoid circuit 131 leading to a solenoid 132 (Figs. 10 and 11) located in a chamber 133 connected to a chamber 134 at an end thereof and in which is pivotally mounted a lever 135 connected to the armature 136 of the solenoid by way of a link 137. At the other end of the chamber 134 are connected air chambers 138 and 139 in which are located spring pressed valves 140 and 141 for controlling communications between the chambers 134 and the chambers 138 and 139. The valves 140 and 141 have stems 142 and 143 extending toward the lever 135 and adapted to be engaged by the lever 135 when operated by the solenoid 132. A compressed air inlet 144 is connected to the chamber 139 and an air exhaust outlet 145 is connected to the chamber 138. From chamber 134 leads the air duct or hose 78 which is connected to the top of the cylinder 72 (Figs. 4 and 6).

If at any time the conveyor motor circuit should be opened and the conveyor stopped, as by opening the switch in the circuit to the motor 6, and if no provision were made for also stopping the spraying as the carriage continues to reciprocate, an excessive amount of spray material would be sprayed on the surface of the article and the coating ruined. In the present invention, this is avoided by opening the shunt circuit 131, which effects a deenergizing of the solenoid and a lowering of the lever 135 whereby the valve 141 is opened and the valve 140 is closed. Compressed air flows by way of duct 144, chamber 139, valve 141, chamber 134, hose 78 to cylinder 72 whereby the piston 73 is forced downwardly with the piston rod 75 to press down the rocker arm part connected to the trigger lifter rod 55 and to depress it and the lifters 67 and 68 and hence permit the triggers 69 and 70 to close off the spray guns. Thus the spray guns are prevented from further spraying the material even though the carriage continues to reciprocate by reason of the motor continuing to operate. However, if desired the two switches 128 and 129 may be so related as to operate together when opening or closing the circuits. In such case the air pressure acts to stop the spraying when the conveyor and the carriage are stopped so that the spraying will not continue at one point on the article and thus spoil the coating.

When the solenoid 132 is again energized, as when the switches 128 or 128 and 129 are closed, the lever 135 is raised, the valve 141 closed, and the valve 140 opened so that air is exhausted from the cylinder 72 by way of the hose 78, chamber 134, valve 140, chamber 138 and outlet 145 into the atmosphere, the spring 75 in the piston chamber 72 acting to raise the piston 73 and the piston rod 75, whereby the spring 60 raises the trigger operating rod 55 and hence the triggers 69 and 70 to again open the guns for spraying, provided the cam roller 80 is off of the cam 81, and in which case the rocker arm 56 is rocked to lower the cam roller 80.

In some cases it might be desirable when stopping the machine that the spray be not stopped within its stroke of spraying but be continued to finish its spraying stroke and then stop. That may be effected by the means shown in Fig. 14,

in which a shunt circuit 146 and 146¹ is connected to the circuits 126 and 127, and the main circuit 130, and to contacts 147 and 148 respectively carried by an arm 149 fixed to the rocker lever 56 and to a fixed part 150 of the device. If the switches are opened during the spraying stroke, the contacts 147 and 148 are in closed circuit condition at that time, since the cam roller 80 is moving between the cams 81, and the current continues by way of the shunt circuit 146—146¹ to the motors 6 and 93. As the carriage approaches the end of its stroke, the roller 80 contacts a cam 81 and hence the rocker arm 56 is rocked to the position shown in Fig. 14, whereby the circuit 146—146¹ is opened by reason of the separation of the contacts 147 and 148, and hence both the conveyor and the carriage stop at the end of the spraying stroke, the spraying also stopping by reason of the downward movement of the trigger rod 55.

The circuits 126 and 127, between the switches 128 and 129 and the motors 6 and 93, are provided with relay controlled cutout switches or circuit breakers 163 and 164 carried on a shaft or rod 165 extending through solenoids 169 and 170. One end of the shaft 165 is connected to a spring 167 and the shaft carries armatures 166 and 168 which are operative in the solenoids 169 and 170. These solenoids are connected by way of shunt circuits 171 and 172 to the circuit portion 146¹, these circuits 171 and 172 being connected to the returns of 146¹ respectively to the circuits 126 and 127.

Assuming the switch 128 to be opened, (switch 129 being closed) and the carriage at a point where the contacts 147 and 148 are closed, the motor 6 will continue to run to operate the conveyor until the carriage has moved to where the rocker arm is operated by the cam 81 and the contacts 147 and 148 open, which is at the end of the spray stroke. This opens the circuit 146—146¹, and the solenoid 169 becomes deenergized, so that the switches 163 and 164 open under the force of the springs 167 and 168, thus opening the circuits to the motors 6 and 93 and stopping the conveyor and the carriage at the end of the spraying stroke, the spraying being also stopped because of the rocker arm being rocked by the cam 81. If it be assumed that switch 129 be opened (switch 128 being closed) and with the carriage at some intermediate point of the spray stroke, the circuit 146—146¹ is in closed condition, and the contacts are closed. As soon as the rocker arm is rocked by the cam 55 at the end of the spray stroke, the solenoid 170 becomes deenergized and the switches 163 and 164 are opened under the force of spring 167, and the motors 6 and 93 stop, thus stopping the conveyor and the carriage at the end of the spray stroke.

If both switches 128 and 129 be opened together the operation is obvious from the above description. The values of the solenoids 169 and 170 and the strength of the spring 167 are such that it is necessary that both solenoids be energized to hold the switches 163 and 164 closed against the force of the spring 167, and that when one solenoid is deenergized the other solenoid is not sufficiently strong to hold the switches 163 and 164 closed against the force of the spring 167.

The circuit 126 to the conveyor motor 6 (Fig. 11) preferably has an overload circuit breaker 162 of any suitable type and so associated with the switch 128 (of any suitable type) as to cause an opening of the circuit 126 upon the jamming

or otherwise preventing the proper driving of the conveyor.

In cases where long narrow objects are to be sprayed, it may be desired to take advantage of a greater portion of the mechanical stroke of the carriage during which to effect the spraying, or, in other words, a longer spray stroke may be desired than would occur if the reciprocation were straight across the width of the article. For this purpose the carriage support of Fig. 4 and the members carried by it may be supported for rotation about a vertical axis so that the spraying stroke may adjustably be at varying angles to the line of travel of the article on the conveyor. Thus, in Figs. 12 and 13 standards 21 and 22 are mounted upon a turntable 154 rotatable about a center shaft 152 and on a circular track 153, the pedestals 23 and 24 of the standards 21 and 22 being secured to the rim portion of turntable 154 by suitable means, as bolts 155. To the lower side of the rim portion of turntable 154 are fixed brackets 156 and 157 rotatably carrying flanged rollers 158 riding on the circular track 153. At the center the turntable has a bearing hub 159 turnable on a bearing means 160 carried by a supporting hub 161. The rest of the device is identical to that described above. By turning the turntable about as desired the cross beam may be brought to any given angle with reference to the line of travel of the piece to be sprayed. Reference is made to Fig. 15 for showing the different spray paths obtained, the spray path S, when the reciprocation is straight across a narrow piece or article 12a being short as compared to the length of the stroke of the carriage and the parts carried by it. When the machine is so positioned as to reciprocate the spraying device at an angle to the line of travel of the piece 12a, the spray path S¹ as shown, will be longer and will be a larger portion of the length of the stroke of reciprocation of the carriage and the parts carried by it. Any suitable means may be used to lock the turntable in adjusted position.

The ducts or hoses 122, 78 and 119 (Fig. 4) preferably extend upwardly and are supported by a clamp 173 of any suitable form, the clamp being suspended from a spring 174 connected at its upper end to a fixed part, such as the ceiling of the room. This kind of suspension affords a free swinging of the hose segments as the carriage is reciprocated.

While we have herein described and upon the drawings shown a few illustrative embodiments of the invention it is to be understood that the invention is not limited thereto but comprehends other constructions, details, arrangements of parts, features, and the like without departing from the spirit of the invention.

Having thus disclosed the invention, we claim:

1. A spraying device for spraying coating upon the surfaces of articles, comprising a conveyor for moving the article in a given path and at a given speed, a support located near said conveyor, a track carried by said support and disposed transversely of said path and in given spaced relation thereto, a carriage on said track and reciprocable therealong, a sprayer carried by said carriage, means carried by said carriage and connected to said sprayer for starting and stopping the operation of said sprayer during the reciprocation of said carriage, and means carried by said support and connected to said carriage for reciprocating said carriage, said start-

ing and stopping means comprising a rocker rockably carried by said carriage and having an operative connection to said sprayer, a pneumatic device carried by said carriage and connected to said rocker for operating said rocker in the spray stopping direction thereof, said pneumatic device having a valve for admitting air under pressure thereto, means connected to said valve and to said conveyor for the air admitting operation of said valve upon the stopping of said conveyor.

2. A spraying device for spraying coating upon the surfaces of articles, comprising a conveyor for moving the article in a given path and at a given speed, a support located near said conveyor, a track carried by said support and disposed transversely of said path and in given spaced relation thereto, a carriage on said track and reciprocable therealong, a sprayer carried by said carriage, means carried by said carriage and connected to said sprayer for starting and stopping the operation of said sprayer during the reciprocation of said carriage, means carried by said support and connected to said carriage for reciprocating said carriage, a turntable so arranged with reference to said conveyor and carrying said support as to permit the placing of said support at any given angle to the direction of movement of said conveyor.

3. A spraying machine comprising a conveyor for moving spray-receiving objects in one direction, a track extending above and transversely of the conveyor and at a fixed distance with respect to the conveyor on which the objects to be sprayed are conveyed, a carriage mounted for traveling along said track, a spray device assemblage supported by the carriage, means for reciprocating the carriage in timed relation to the movement of the conveyor and with strokes of uniform length, a spray-controlling member carried by the carriage; two actuating members slidably supported by and spaced longitudinally of the track, the said members being disposed in the path of reciprocation of said spray-controlling member and each adapted to operate the spray-controlling member for discontinuing the spraying; and manually operable means operatively connected to said actuating members and for moving the two actuating members toward or away from each other so as to vary the proportion of the time of each stroke of the carrier during which the spraying is effected.

4. A spraying device for spraying coating upon surfaces of articles carried by a conveyor in a given path and at a given speed, comprising a support located near said conveyor, a track carried by said support and disposed transversely of said path and in given fixed spaced relation thereto, a carriage on said track and reciprocable therealong, means carried by said support and connected to said carriage for reciprocating said carriage, a sprayer carried by said carriage; means for determining the time of spraying by said sprayer during the reciprocation of said carriage and sprayer, comprising relatively adjustable spaced cams supported on said support for mutual adjustment to and from each other, an operable common element operatively connected to said cams for mutually adjusting said cams to and from each other when said common element is operated and when said track is in a given fixed distance with respect to the conveyor on which the articles to be sprayed are conveyed, a spring pressed movable member carried by said carriage and operatively connected to said spray-

er, said member having a part so located as to normally move in the space between said cams and to alternately engage said adjusted cams during the reciprocation of said carriage and sprayer.

5. A spraying device for spraying coating upon surfaces of articles carried by a conveyor in a given path and at a given speed, comprising a support located near said conveyor, a track carried by said support and disposed transversely of said path and in given fixed spaced relation thereto, a carriage on said track and reciprocable therealong, means carried by said support and connected to said carriage for reciprocating said carriage, a sprayer carried by said carriage; means for determining the time of spraying by said sprayer during the reciprocation of said carriage and sprayer, comprising relatively adjustable spaced cams supported on said support for mutual adjustment to and from each other, an operable common element operatively connected to and extending from one to the other of said cams for mutually adjusting said cams to and from each other when said common element is operated and when said track is in a given fixed distance with respect to the conveyor on which the articles to be sprayed are conveyed, a spring pressed movable member carried by said carriage and operatively connected to said sprayer, said member having a part so located as to normally move in the space between said cams and to alternately engage said adjusted cams during the reciprocation of said carriage and sprayer.

6. A spraying device for spraying coating upon surfaces of articles carried by a conveyor in a given path and at a given speed, comprising a support located near said conveyor, a track carried by said support and disposed transversely of said path and in given fixed spaced relation thereto, a carriage on said track and reciprocable therealong, means carried by said support and connected to said carriage for reciprocating said carriage, a sprayer carried by said carriage; means for determining the time of spraying by said sprayer during the reciprocation of said carriage and sprayer, comprising relatively adjustable spaced cams supported on said support for mutual adjustment to and from each other, an operable common element operatively connected to and carried by said cams, for mutually adjusting said cams to and from each other when said common element is operated and when said track is in a given fixed distance with respect to the conveyor on which the articles to be sprayed are conveyed, a spring pressed movable member carried by said carriage and operatively connected to said sprayer, said member having a part so located as to normally move in the space between said cams and to alternately engage said adjusted cams during the reciprocation of said carriage and sprayer.

7. A spraying device for spraying coating upon surfaces of articles carried by a conveyor in a given path and at a given speed, comprising a support located near said conveyor, a track carried by said support and disposed transversely of said path and in given fixed spaced relation thereto, a carriage on said track and reciprocable therealong, means carried by said support and connected to said carriage for reciprocating said carriage, a sprayer carried by said carriage; means for determining the time of spraying by said sprayer during the reciprocation of said carriage and sprayer, comprising relatively adjust-

able spaced cams supported on said support for mutual adjustment to and from each other, an operable common element operatively connected to said cams for mutually adjusting said cams to and from each other when said common element is operated and when said track is in a given fixed distance with respect to the conveyor on which the articles to be sprayed are conveyed, a spring pressed rocker pivotally mounted on said carriage to rock in a plane transverse to the line of reciprocation of said carriage and sprayer and operatively connected at an end thereof to said sprayer, said rocker having its other end so located as to normally move in the space between said cams and to alternately engage said adjusted cams during the reciprocation of said carriage.

8. A spraying device for spraying coating upon the surfaces of articles, comprising a conveyor for moving the article in a given path and at a given speed, a support located near said conveyor, a track carried by said support and disposed transversely of said path and in given fixed spaced relation thereto, a carriage on said track and reciprocable therealong, means carried by said support and connected to said carriage for reciprocating said carriage, an electric motor for operating the latter means, a sprayer carried by said carriage, means carried by said carriage and connected to said sprayer for starting and stopping the operation of said sprayer during the reciprocation of said carriage, said starting and stopping means comprising relatively adjustable spaced cams supported on said support, an operable element operatively connected to said cams for adjustment of said cams to and from each other when said element is operated and when said track is in a given fixed distance with respect to the conveyor on which the articles to be sprayed are conveyed, and a spring pressed movable member carried by said carriage and operatively connected to said sprayer, said member having a part so located as to normally move between said cams and to alternately engage said cams during the reciprocation of said carriage and sprayer; an emergency device associated with said starting and stopping means for independently starting and stopping the operation of said sprayer, comprising a spring pressed actuating member carried by said carriage and located adjacent to said spring pressed movable member to act on said spring pressed movable member, an electromagnetic device connected to the circuit of said motor, and an actuating element connected to said electromagnetic device and to said spring pressed actuating member to cause the latter to act on said spring pressed movable member when the electromagnet is deenergized upon the opening of the motor circuit to stop the operation of said sprayer.

9. A spraying device for spraying coating upon the surfaces of articles, comprising a conveyor for moving the article in a given path and at a given speed, a support located near said conveyor, a track carried by said support and disposed transversely of said path and in given fixed spaced relation thereto, a carriage on said track and reciprocable therealong, means carried by said support and connected to said carriage for reciprocating said carriage, an electric motor for operating the latter means, a sprayer carried by said carriage, means carried by said carriage and connected to said sprayer for starting and stopping the operation of said sprayer during the reciprocation of said carriage, said starting and stopping means comprising relative-

ly adjustable spaced cams supported on said support, an operable element operatively connected to said cams for adjustment of said cams to and from each other when said element is operated and when said track is in a given fixed distance with respect to the conveyor on which the articles to be sprayed are conveyed, and a spring pressed rocker rockably carried by said carriage and operatively connected to said sprayer at an end of said rocker, the other end of said rocker being so located as to normally move between said cams and to alternately engage said cams during the reciprocation of said carriage and sprayer; an emergency device associated with said starting and stopping means for independently starting and stopping the operation of said sprayer, comprising a pneumatically operated device car-

ried by said carriage and located adjacent said rocker to act on said rocker when said pneumatically operated device is operated, an electromagnetic device connected to the circuit of said motor, a valve means operatively connected to said electromagnetic device, pressure fluid ducts connected to said valve means and to said pneumatically operated device for conducting pressure fluid to and from said pneumatically operated device when said electromagnetic device is deenergized and energized to operate said valve means upon the opening and closing of the circuit of said motor.
